149,199

DESIGN FOR A FRUIT JUICER

Archibald L. Lynne, Chicago, Ill.

Application August 13, 1946, Serial No. 132,492

Term of patent 3½ years

(Cl. D89—1)

To all whom it may concern:

Be it known that I, Archibald L. Lynne, a citizen of the United States, residing at Chicago, in the county of Cook and State of Illinois, have invented a new, original, and ornamental Design for Fruit Juicers, of which the following is a specification, reference being had to the accompanying drawing, forming part thereof.

Fig. 1 is a front elevational view of a fruit juicer, showing my new design;

Fig. 2 is a top plan view, and

Fig. 3 is a side elevational view.

I claim:

The ornamental design for a fruit juicer, as shown.

ARCHIBALD L. LYNNE.
